Primary Examiner — Sheryl Lane*Assistant Examiner* — Ieisha Price(74) *Attorney, Agent, or Firm* — Thompson Hine LLP(57) **CLAIM**

The ornamental design for a folder with spine features, as shown and described.

DESCRIPTION

FIG. 1 is a top view of the folder with spine features; FIG. 2 is a top perspective view of the folder with spine features of FIG. 1; and,

FIG. 3 is a perspective view of the folder with spine features of FIG. 2, in a folded and closed condition.

The broken lines in the drawings illustrate portions of the folder with spine features and form no part of the claimed design.

The perimeter of folder with spine features, the features shown in full lines and areas rendered with shading are to be understood to be the claimed design. The surfaces without shading are not the claimed design and form no part thereof.
